UNITED STATES PATENT OFFICE.

EDWIN C. SALTER, OF PHILADELPHIA, PENNSYLVANIA.

KEY-HOLE GUARD.

SPECIFICATION forming part of Letters Patent No. 301,283, dated July 1, 1884.

Application filed February 27, 1884. (No model.)

To all whom it may concern:

Be it known that I, EDWIN C. SALTER, a citizen of the United States, residing in the city and county of Philadelphia, State of Pennsylvania, have invented a new and useful Improvement in Lock-Guards, which improvement is fully set forth in the following specification and accompanying drawings, in which—

10 Figures 1 and 2 are side elevations, partly sectional, of a lock-guard embodying my invention. Fig. 3 is a front end view thereof. Fig. 4 is a section in line $x-x$, Fig. 1. Fig. 5 is a view of the interior of the lock employed.

15 Similar letters of reference indicate corresponding parts in the several figures.

My invention consists of a lock-guard constructed and operating substantially as hereinafter fully set forth.

20 Referring to the drawings, A represents a spindle, which is formed with a bit, B, both adapted to enter a key-hole and body of a lock, and said bit to engage with the face of a ward or casing thereof.

25 C represents a bar, which is connected at its front end with a lock, D, and is free at the other end, and extends parallel with the spindle, so as to enter the key-hole and body of the lock, said lock D having an opening in its casing to permit the passage therethrough of the spindle A, thus supporting said lock D. The spindle is formed with lugs E at intervals, the surfaces whereof are threaded for the engagement of a nut, F, which tightens

30 against the lock D. The lock D has within it a spring-dog, G, and a stop, G', whereby when the spindle A is turned the lug E which is inserted in said lock D is engaged by the dog G, and thereby secured, and cannot be 35 moved in either direction, owing to said dog G and stop G', a key, H, however, being provided for properly moving the dog G and releasing the lug, whereby the spindle may be turned to register with the key-hole of the lock D, and thereby withdrawn therefrom.

40 The operation is as follows: After the bolt has been properly locked and the key thereof withdrawn, the spindle A is inserted with the bit B above into the lock through the key-hole and raised. The lock D is then fitted

on the spindle and pushed in thereon to full extent, thus also inserting the bar C in the key-hole below the spindle. The spindle is then rotated by means of a key or handle, (shown in the present case detachably fitted 55 in a notch in the spindle,) whereby the lug E which is within the lock D is locked by the dog G and prevented from rotation, it being seen that the bit B is in the space between the wards or a ward and the lock-casing. The 60 nut F is now screwed on the spindle and tightened against the lock D, thus forcing the bit B against the respective ward and the lock D against the lock-casing, as seen in Fig. 1, whereby rotation of the spindle from without 65 is prevented. As the bar C is immovable and occupies the portion of the space within the lock coinciding with the key-hole, should the spindle A be forcibly rotated to overcome the nut F and the dog G or stop G', the 70 bit B abuts against the bar C, whereby the spindle cannot be pushed out of the key-hole. When the nut F is loosened and the key H properly inserted in the lock D and rotated, it disengages the dog G from the lug E, where- 75 by the lock D may be removed from the spindle, carrying with it the bar C. The spindle may then be rotated to cause the bit B to coincide with the key-hole, thus permitting the withdrawal of the spindle and clearing the 80 key-hole for the introduction of the key of the lock proper.

In order to adjust the bar C to smaller locks, I form the same of parts hinged together, so that the one may be folded within 85 or on the other, and thus reduce the length of the bar.

The plate D' of the casing of the lock D covers the key-hole, and is forced against the wall thereof by the nut F; hence the insertion of a piece of wire or an implement from without to reach the nut and loosen it is prevented.

Having thus described my invention, what I claim as new, and desire to secure by Letters 95 Patent, is—

1. In a lock or key-hole guard, a spindle formed with a bit, B, and a series of lugs, E, a lock which is fitted on said spindle and has its bolt or dog adapted to engage with one of 100

the lugs E, and a bar connected with said lock, substantially as and for the purpose set forth.

2. In a lock or key-hole guard, a spindle formed with a bit, B, and a series of screw-threaded lugs, E, a lock fitted on said spindle and having its bolt or dog adapted to engage with one of the said lugs, a bar connected with

10 said lock, and a nut fitted on the lugs of the spindle, said parts being combined and operating substantially as and for the purpose set forth.

EDWIN C. SALTER.
